UNITED STATES PATENT OFFICE.

IRVING A. TAYLOR, OF WORCESTER, MASSACHUSETTS, ASSIGNOR TO SANFORD RILEY STOKER CO. LTD., OF WORCESTER, MASSACHUSETTS, A CORPORATION OF MASSACHUSETTS.

FURNACE FEEDING MECHANISM.

Application filed February 21, 1919, Serial No. 278,472. Renewed December 8, 1921. Serial No. 520,990.

To all whom it may concern:

Be it known that I, IRVING A. TAYLOR, a citizen of the United States, residing at Worcester, in the county of Worcester and 5 State of Massachusetts, have invented a new and useful Furnace Feeding Mechanism, of which the following is a specification.

This invention relates to feeding mechanism for a furnace of the underfeed type, in which a series of parallel retorts are fed by separate plungers or rams which advance the fuel from an overhead supply to the bottom of the retorts and thence to 15 the underside of the fuel bed. These rams are subject to heavy strain and are preferably operated singly or in small sections, through continuously driven worm gear mechanism.

20 Heretofore, in the usual construction, all feeding mechanism of the type described has been driven at the same speed and fuel has been fed to each retort at the same rate throughout the furnace, no provision being 25 made for varying the delivery of fuel at different points of the fuel bed, except by stopping one or more rams.

In case of accidental stoppage of one section, as when a retort is blocked by a foreign substance in the fuel, it is desirable 30 that this retort section be thereafter operated faster in order to even up the fuel bed. It is also highly desirable that a furnace be provided with means for obtaining different rates of fuel feed in different 35 parts of the same fuel bed, in order to offset the effect of unequal draft resistance, due to unequal depth of fuel in the fuel bed. Preferably also the feeding mechanisms will each have a regular and continuous motion at each available speed,

40 In view of these considerations it is one object of my invention to provide a continuously operated feeding mechanism for an underfeed furnace which is adapted to feed fuel to different retort sections under the same continuous fuel bed at rates which may be independently controlled.

An additional object of my invention is 45 to provide a construction in which a continuous driving shaft may be used for a plurality of multi-speed gear drives in the same or adjacent furnaces, doing away with the usual separate connections to an under- 55 lying counter-shaft.

With these and other objects in view, my invention in its preferred form relates to an underfeed furnace construction comprising a single furnace fire box and a stoker mechanism therefor having a series 60 of retort sections and a series of coal feeding devices adapted to force fuel into said retorts under a continuous fuel bed, these devices being driven by selectively controlled worm gear mechanisms which permit fuel to be fed at different rates to the different retort sections. In the specific embodiment of my invention illustrated in the drawings, I have shown a simplified construction involving a series of multi-speed 70 worm gear drives and a separate manual controlling device for each section whereby any section may be rendered inoperative or may be operated at a relatively high or relatively low speed.

75 My invention further relates to arrangements and combinations of parts herein-after described and more particularly pointed out in the appended claims.

A preferred form of my invention is 80 shown in the drawings in which—

Fig. 1 is a partial front elevation of several retorts, in an underfeed furnace;

Fig. 2 is a vertical sectional view taken along the line 2—2 in Fig. 1;

Fig. 3 is a vertical sectional view of the two-speed gear box taken along the line 3—3 in Fig. 4;

Fig. 4 is a horizontal sectional view of the gear box taken along the line 4—4 in 90 Fig. 3, and

Fig. 5 is a detail front elevation of the controlling lever.

Referring to Figs. 1 and 2, I have indicated in a general way certain parts of 95 a common form of underfeed furnace, the furnace being built up of a plurality of retorts each provided with a hopper 10 and with a coal feeding plunger or ram 11 slideable in a cylindrical casing 12, which also 100 supports the hopper 10.

Each ram 11 is connected by a connecting rod 13 to a crank shaft section 14, the length of the sections of the shaft 14 varying in practice and two or more rams being commonly actuated from a single section. A separate gear box 15 is provided for each section of the crank shaft 14, the side walls of the gear box supporting the bearings for the crank shaft 14, and the 110

whole mechanism being protected by a hinged cover 16. A driving shaft 17 extends continuously through the entire series of gear boxes 15.

5 For convenience in assembling, this shaft 17 may be made up in separate parts connected by flexible couplings 18 as shown in Fig. 1, but the shaft is in effect continuous and commonly has a single driving connection to a convenient source of power (not shown).

The driving shaft 17 is provided with bearings 19 and 20 in each gear box 15, these bearings having suitable provision to prevent the escape of oil from the gear box. A worm shaft 21 is rotatable in bearings 22 and 23 in the lower front part of the gear box, said shaft having a worm 24 formed in its middle portion and having gears 25 and 26 keyed to its end portions. The outer side of each gear is provided with an enlarged bearing surface which engages the finished inner surface of one of the side plates of the gear box, and thus 25 acts as a thrust bearing for the worm shaft 21.

The gear 25 meshes with a pinion 27 loose on the driving shaft 17, and the gear 26 meshes with a gear 28 also loose on the shaft 17. As shown in the drawings, the gears 26 and 28 are of substantially equal size, while the gears 27 and 25 give a speed reduction of approximately two to one. Each of the gears 27 and 28 is provided with a clutch member 30 on its inner face adapted to engage a corresponding member 31 formed on the ends of a sliding sleeve 32 keyed to the shaft 17, but freely movable axially thereon. The sleeve 32 is grooved 40 to receive arms 33 (Fig. 3) of a yoke 34 mounted on a horizontal rod 35 to the outer end of which a hand lever 36 is secured. The lever 36 is provided with a segmental slot 37 (Fig. 5) through which extends a latch pin 38 (Fig. 3) pivoted at 39 to the gear box casing. The slot 37 has a notch 40 in its lower surface into which the latch 38 drops when the lever 36 is in neutral position. When the lever is in either its right-hand or left-hand operative position, the latch is at the corresponding end of the slot 37, and the lever is held in position by its own weight.

The worm 24 meshes with a worm wheel 41 (Fig. 3) keyed to a cross shaft 42 to which is also secured a second worm 43 meshing with a large worm wheel 44 on a section of the crank shaft 14. Suitable provision is made at each end of the shaft 42 so that the thrust of the worm 43 may be taken by casing 15.

With this construction it will be seen that the driving shaft 17 can be continuously rotated and can extend through any desired number of gear boxes 15, each gear box

remaining inoperative so long as its clutch sleeve 32 is in neutral position. By swinging the hand lever 36 to the right or left, the driving shaft may be connected to the corresponding section of the crank shaft 70 to rotate the same at either high or low speed.

I have thus provided a simple and economical multi-speed worm gear drive for all of the coal feeding rams of an underfeed furnace, and have also provided for separately controlling the speed and operation of the rams connected to each section of the crank shaft. In this way I can maintain uniform conditions throughout the 80 furnace, varying the feed in any section which is either ahead or behind the desired average condition of the fuel bed.

It will also be evident that changes and modifications can be made in the construction herein shown by those skilled in the art without departing from the spirit and scope of my invention as set forth in the claims, and I do not wish to be otherwise limited to the details herein disclosed, but 90 what I do claim is:—

1. In an underfeed furnace, a plurality of coal feeding rams, crank shaft sections connected to drive said rams, a change speed worm gear mechanism for each section through which each section of said crank shaft may be operated at a selected speed, a single driving shaft extending continuously through said gear mechanisms, and means to selectively connect said driving shaft to any section of said crank shaft through its associated change gear mechanism to drive said shaft section continuously and independently at a selected reduced speed. 105

2. In an underfeed furnace, a plurality of coal feeding rams, crank shaft sections connected thereto, a continuous driving shaft, and driving connections between said shaft and said sections, said connections each including a worm shaft, a high speed positive drive to said worm shaft, a low speed positive drive to said worm shaft, and a manually controlled clutch mechanism effective to render either drive operative to actuate said 110 worm shaft continuously at a selected reduced speed. 115

3. In an underfeed furnace, a plurality of coal feeding rams, crank shaft sections connected thereto, a continuous driving shaft, 120 and driving connections between said shaft and said sections, said connections each including a worm shaft, a casing therefor, a gear fixed at each end of said worm shaft, and gears on said continuous driving shaft 125 meshing therewith, the gears on said worm shaft having side faces engaging the inner surfaces of said casing and forming thrust bearings therewith for said worm shaft.

4. In an underfeed furnace, a coal feeding 130

ram, a driving shaft, two-speed gear connections between said shaft and said ram, said connections including a clutch, a hand lever controlling said clutch and held by gravity in either one of two operative positions, and means to hold said lever and clutch in neutral inoperative position, said means comprising a pivoted latch cooperating with a notched opening in said lever when the latter is in neutral position.

5. In an underfeed furnace, a coal feeding ram, a crankshaft connected to reciprocate said ram, a driving shaft, change speed worm gear mechanism interposed between 15 said driving shaft and said crankshaft, and controlling means by which said mechanism

may be adjusted to drive said crankshaft continuously at a selected reduced speed.

6. In an underfeed furnace, a coal feeding ram, a crankshaft connected to reciprocate 20 said ram, a driving shaft, a relatively high speed positive continuous drive from said driving shaft to said crankshaft; a relatively low speed positive continuous drive from said driving shaft to said crankshaft, and 25 manually controlled devices effective to render either drive operative to rotate said crank shaft continuously at a selected reduced speed.

In testimony whereof I have hereunto af- 30 fixed my signature.

IRVING A. TAYLOR.
